[57] CLAIM

The ornamental design for a beverage dispensing machine, substantially as shown and described.

DESCRIPTION

FIG. 1 is a downward looking perspective view of a beverage dispensing machine, showing my new design; FIG. 2 is a front elevational view thereof;

FIG. 3 is a side elevational view thereof, the opposite side being substantially a mirror image of FIG. 3; and FIG. 4 is a top plan view thereof.

The bottom and rear side, are planar and unornamented.
